Primary Examiner — Cathy A MacCormac**CLAIM**

The ornamental design for a multi-function imaging and printing device, substantially as shown and described.

DESCRIPTION

FIG. 1 is a right-front perspective view of the design for the multi-function imaging and printing device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions shown in broken lines are for illustrative purposes only and form no part of the claimed design.
